UNITED STATES PATENT OFFICE.

LAURENCE A. HAWKINS, OF SCHENECTADY, NEW YORK, ASSIGNOR, BY MESNE ASSIGNMENTS, TO THE UNION SWITCH AND SIGNAL COMPANY, A CORPORATION OF PENNSYLVANIA.

SIGNAL SYSTEM.

1,102,916.

Specification of Letters Patent.

Patented July 7, 1914.

Application filed November 29, 1907. Serial No. 404,211.

To all whom it may concern:

Be it known that I, LAURENCE A. HAWKINS, a citizen of the United States, residing at Schenectady, in the county of Schenectady, State of New York, have invented certain new and useful Improvements in Signal Systems, of which the following is a specification.

My invention relates to signal systems for single-track sections of electric roads of the type in which counting mechanisms are employed, so that a plurality of cars passing in the same direction may occupy the section simultaneously, and the signal at the out-going end will not be cleared until the last car has passed from the section.

The object of my invention is to provide a novel system of this character, which shall be reliable in its indications, simple in its apparatus, and economical in its construction and installation.

A system of this character should fulfill the following requirements: The first car entering the single-track section should put the signal at the opposite end at danger, and the operation of the signal at the opposite end should give an answer-back indication, so that the motorman can know positively that the signal at the opposite end has operated. A caution signal should be given at the end entered by the car, so as to indicate to a following car that the section is occupied by a car passing in the same direction. If the second car follows the first one into the section, the apparatus should be actuated so that the signal at the opposite end cannot clear until both cars have left the section. Furthermore, the second car should also receive an answer-back signal to show that the mechanism at the out-going end has operated to count that car. The same operation should be repeated as each succeeding car enters the section.

If a car enters the section and backs out, it must restore the signals to their proper condition. If a car over-runs a danger signal;—that is, enters a section already occupied by a car moving in the opposite direction, as may occur when the danger signal is thrown in the face of the motorman when he is so close to the signal that he is unable to stop before passing it, the signals should be left in proper condition when the car which is wrongfully in the section

backs out. If two cars enter an unoccupied section from opposite ends simultaneously, neither car should set the signals nor receive the answer-back or proceed indication. The signals should preferably comprise both lamps for night service and semaphores or banners for day service. These devices should be controlled properly and automatically for the different car-movements, above specified, with a minimum number of line-wires extending through the block. Under no condition should an answer-back clear signal be given, unless the signal at the other end of the block is positively at danger.

The system to be described in the following specification fulfills all the above requirements, and the desired operations are obtained with only two line-wires. In order to obtain these results, the system comprises a number of novel features, which will be specifically pointed out in the appended claims, and which will best be understood by reference to the accompanying drawings, in which—

Figure 1 shows diagrammatically a signal system for a single-track section of a trolley road, arranged in accordance with my invention; and Fig. 2 shows a modification of the same.

Signal mechanisms for both ends of a single-track section are shown. The two mechanisms are similar in every respect, and corresponding parts are indicated by corresponding numerals, the numerals for the left-hand mechanism being primed. The right-hand mechanism will be described, and it will be understood that this description applies equally to the left-hand mechanism.

1 represents the position of the trolley wire extending through the single-track section.

2 and 3 represent two contacts which are arranged to be connected to the trolley-wire 1 by the movable contact 4, when a car, respectively, enters and leaves the section from the right-hand end. The arrangement of the contacts 2, 3 and 4 is indicated diagrammatically. In practice any well known construction of trolley contact may be employed, many of which are well known in the art. It is to be understood that, as usual in such trolley contacts, the device is

arranged so that the engagement of contact 4 with contacts 2 and 3 is not merely instantaneous, but is prolonged for a sufficient length of time to allow the signal mechanism to be actuated. The contact 2 is connected through a resistance 5 and lamp 6 in parallel to one terminal of the coils 7-7 of a polarized relay 8. 9 represents the polarizing coil of the relay, which is connected to the trolley-wire through a resistance 10. This resistance may be in the form of a lamp so that if the circuit of the polarized winding should be broken, notice would be given by the extinguishing of the lamp. As an added precaution, the central member of the relay 8, on which the coil 9 is mounted, may be formed from a hard steel permanent magnet. The armature of the relay normally stands in the position shown. The other terminal of the coils 7 is connected to a line-wire 11, which extends to the signal mechanism at the opposite end of the single-track section.

12 represents a resistance, which is connected between the right-hand terminal of coils 7 and ground.

13 represents a step-by-step device which is shown diagrammatically as a ratchet-wheel arranged to be moved in opposite directions step-by-step by the "counting-in" magnet 14 and the "counting-out" magnet 15. The armature of the magnet 14 is provided with a contact 16, which, when the magnet is energized, short-circuits the greater portion of resistance 12.

17 represents a switch-arm or contact which is normally supported by a pin on the ratchet 13 in such manner that when the ratchet is moved one step by the counting-in magnet 14, the arm 17 is allowed to fall from its front contacts to its back contacts. A further movement of the ratchet 13 in the same direction does not move the arm 17, which remains in the position just described until the ratchet 13 is restored to its original position, when the pin carried by the ratchet engages the arm in moving through the last step and shifts it from its back contacts to its front contacts.

18 represents a magnet which is normally connected through the front contacts on the arm 17 to the trolley-wire, and is consequently normally energized.

19 represents a semaphore arm which is normally held raised in clear position, as shown, but which is dropped to danger position when magnet 18 is deenergized.

20 represents a red lamp, which when illuminated serves as the danger signal at night, and which when the arm 17 is in engagement with its back contacts is connected through the resistance 21 to trolley.

22 represents a second line-wire, which is connected to the contact 3, and also to both front and back contacts on the semaphore

arm 19. When the semaphore arm is in its clear position, line-wire 22 is connected through lamp 23 and resistance 24 to trolley. Lamp 23, which may be a green lamp, serves as the caution signal. When the semaphore arm 19 is in danger position line-wire 22 is connected to counting-out magnet 15; the other terminal of which is grounded.

The operation of the system is as follows: When a car enters the block from the right-hand end, a circuit is closed from trolley-wire 1, through contacts 4 and 2, resistance 5 and lamp 6 in parallel, coils 7 of polarized relay 8, line-wire 11, coils 7' of relay 8', and resistance 12' to ground. There is also a branch circuit to ground from the right-hand terminal of coils 7 of relay 8, through resistance 12. Resistances 12 and 12' are high compared to the resistances of coils 7 and 7', so that the current divides nearly equally between the two paths to ground. Resistances 5 and resistances 12 and 12' are so proportioned that the voltage-drop across resistance 5 is not sufficient to illuminate lamp 6. Polarized relays 8 and 8' are so connected that neither responds to a current flowing through them toward line-wire 11, while each responds to a current flowing through them from line-wire 11. Consequently, when the circuit, as traced above, is established, relay 8 is not affected, but relay 8' shifts its armature into engagement with its contacts. A circuit is then closed from trolley-wire 1 through the contacts of relay 8' and counting-in magnet 14' to ground. Magnet 14' is energized and shifts ratchet-wheel 13' one step in a counter-clockwise direction, allowing arm 17' to move from its front to its back contacts. This breaks the circuit of magnet 18', allowing semaphore 19' to drop to danger position, and closes the circuit of red lamp 20'. The movement of arm 19' to danger position disconnects lamp 23' from line-wire 22 and establishes the following circuit: from trolley-wire 1 at the right-hand end of the section, through resistance 24, lamp 23, front contacts of semaphore 19, line-wire 22, back contacts of semaphore 19' and counting-out magnet 15' to ground. The resistance of resistance 24 and lamp 23 is too great to permit sufficient current to pass to operate magnet 15', but lamp 23 is illuminated, showing that semaphore 19' is at danger position, and at the same time serving as a caution signal to indicate to following cars that the block is occupied. A second answer-back indication is given by means of contact 16'. When the counting-in magnet 14' operates, contact 16' short-circuits the greater part of resistance 12', thereby momentarily increasing the current flowing through line-wire 11, sufficiently to illuminate momentarily lamp 6. After the first car has entered the block, if a second

car enters the block, the circuit is closed from trolley-wire 1, through contacts 4 and 2, resistance 5 and lamp 6 in parallel, coils 7 of polarized relay 8, line-wire 11, coils 7' of relay 8', and resistance 12' to ground.

Magnet 14' is energized and shifts ratchet-wheel 13' one step in a counter-clockwise direction, allowing arm 17' to move from its front to its back contacts. This breaks the circuit of magnet 18', allowing semaphore 19' to drop to danger position, and closes the circuit of red lamp 20'. The movement of arm 19' to danger position disconnects lamp 23' from line-wire 22 and establishes the following circuit: from trolley-wire 1 at the right-hand end of the section, through resistance 24, lamp 23, front contacts of semaphore 19, line-wire 22, back contacts of semaphore 19' and counting-out magnet 15' to ground. The resistance of resistance 24 and lamp 23 is too great to permit sufficient current to pass to operate magnet 15', but lamp 23 is illuminated, showing that semaphore 19' is at danger position, and at the same time serving as a caution signal to indicate to following cars that the block is occupied. A second answer-back indication is given by means of contact 16'. When the counting-in magnet 14' operates, contact 16' short-circuits the greater part of resistance 12', thereby momentarily increasing the current flowing through line-wire 11, sufficiently to illuminate momentarily lamp 6. After the first car has entered the block, if a second

car enters the block, the circuit is closed from trolley-wire 1, through contacts 4 and 2, resistance 5 and lamp 6 in parallel, coils 7 of polarized relay 8, line-wire 11, coils 7' of relay 8', and resistance 12' to ground.

Magnet 14' is energized and shifts ratchet-wheel 13' one step in a counter-clockwise direction, allowing arm 17' to move from its front to its back contacts. This breaks the circuit of magnet 18', allowing semaphore 19' to drop to danger position, and closes the circuit of red lamp 20'. The movement of arm 19' to danger position disconnects lamp 23' from line-wire 22 and establishes the following circuit: from trolley-wire 1 at the right-hand end of the section, through resistance 24, lamp 23, front contacts of semaphore 19, line-wire 22, back contacts of semaphore 19' and counting-out magnet 15' to ground. The resistance of resistance 24 and lamp 23 is too great to permit sufficient current to pass to operate magnet 15', but lamp 23 is illuminated, showing that semaphore 19' is at danger position, and at the same time serving as a caution signal to indicate to following cars that the block is occupied. A second answer-back indication is given by means of contact 16'. When the counting-in magnet 14' operates, contact 16' short-circuits the greater part of resistance 12', thereby momentarily increasing the current flowing through line-wire 11, sufficiently to illuminate momentarily lamp 6. After the first car has entered the block, if a second

car enters the block, the circuit is closed from trolley-wire 1, through contacts 4 and 2, resistance 5 and lamp 6 in parallel, coils 7 of polarized relay 8, line-wire 11, coils 7' of relay 8', and resistance 12' to ground.

Magnet 14' is energized and shifts ratchet-wheel 13' one step in a counter-clockwise direction, allowing arm 17' to move from its front to its back contacts. This breaks the circuit of magnet 18', allowing semaphore 19' to drop to danger position, and closes the circuit of red lamp 20'. The movement of arm 19' to danger position disconnects lamp 23' from line-wire 22 and establishes the following circuit: from trolley-wire 1 at the right-hand end of the section, through resistance 24, lamp 23, front contacts of semaphore 19, line-wire 22, back contacts of semaphore 19' and counting-out magnet 15' to ground. The resistance of resistance 24 and lamp 23 is too great to permit sufficient current to pass to operate magnet 15', but lamp 23 is illuminated, showing that semaphore 19' is at danger position, and at the same time serving as a caution signal to indicate to following cars that the block is occupied. A second answer-back indication is given by means of contact 16'. When the counting-in magnet 14' operates, contact 16' short-circuits the greater part of resistance 12', thereby momentarily increasing the current flowing through line-wire 11, sufficiently to illuminate momentarily lamp 6. After the first car has entered the block, if a second

car moving in the same direction reaches the right-hand end of the section, it will be warned by lamp 23 that there is a car in the section ahead of it, and will consequently proceed under control. As it enters the section and brings contact 4 into engagement with contact 2, polarized relay 8' is again actuated and counting-in magnet 14' shifts ratchet 13' another step. This movement of the ratchet does not disturb the position of arm 17', nor does it affect the signals that have already been set; but it prevents the arm 17' from being restored to its normal position, so as to clear the signals until the ratchet 13 has been returned two steps. The operation of the magnet 14' in shifting the ratchet 13' this second step again short-circuits the greater portion of resistance 12', so as to again momentarily illuminate lamp 6. Lamp 6 thus acts as an answer-back signal for each succeeding car, giving assurance to the motorman that his car has been properly counted in by the mechanism at the opposite end of the block. When the first car leaves the section at the left-hand end, a circuit is closed from trolley-wire 1, through contacts 4' and 3', directly to line-wire 22. This connects counting-out magnet 15' directly between trolley-wire and ground, so that this magnet operates to return ratchet 13' one step in a clockwise direction. The same thing occurs if a car that has entered backs out instead of proceeding through the section; the only difference being that the connection from trolley-wire 1 to line-wire 22 is formed through contacts 4 and 3, instead of 4' and 3'. In either case, counting-out magnet 15 is not affected, since its circuit is open at the back contacts of semaphore 19, which is at clear position. If a car over-runs a danger signal, and then backs out, as is necessary for it to do, the signals will be left in proper condition. For instance, suppose semaphore 19' is at danger, but a car approaching from the left over-runs contact 4'; a circuit is then closed from trolley-wire 1 through contacts 4' and 2' to the upper back contact on arm 17', and through these contacts to line-wire 11. The right-hand terminal of coil 7' is thus connected directly to trolley-wire, while the left-hand terminal is connected to trolley-wire through resistance 5'. Since coils 7' are of low resistance, as has been said heretofore, current will flow through these coils from right to left at the same time that current passes through line-wire 11, and through coils 7 and resistance 12 to ground,—that is, current passes from line-wire 11 through both polarized relays, so that both polarized relays are actuated, and both counting-in magnets 14 and 14' are consequently energized, and ratchets 13 and 13' are both shifted one step. This throws semaphore 19 to danger,

and since semaphore 19' is already at danger, both counting-out magnets 15 and 15' are connected to line-wire 2. Therefore, when the car that has wrongfully entered the left-hand section backs out again and throws contact 4' into engagement with contact 3', both magnets 15 and 15' are actuated, and both ratchets are returned to the positions they occupied before the car entered the section. If two cars enter a clear section simultaneously from opposite ends, both ends of line-wire 11 are connected to trolley-wire and are at the same potential, so that no current flows through the line wire, the signals are not set, and no answer-back indication is received by either car. Both cars must back out and the first to enter the section again gets control of the signals.

Fig. 2 shows a modification of the system, which is the same in its essential features as the system shown in Fig. 1, but which differs in certain details. In place of the movable contact 4 of Fig. 1, the trolley-wire is shown diagrammatically as provided with frogs or turn-outs for deflecting the trolley-wheel into engagement with the contact 2 or 3, according to the direction of movement of the car. The contact arrangement of either Fig. 1 or 2, may be used with the circuit connections of either figure. The specific arrangement of the trolley contact forms no part of my invention. In Fig. 2, the polarized relays are omitted and the counting-in magnets 14 and 14' are placed in series with the line-wire 11, and are themselves provided with polarizing coils. In place of semaphores controlled electrically by the contact arms 17 and 17', light banners 19 and 19' are employed for the day signals, and are mechanically connected to the contact arms 17 and 17'. The operation of this modification is substantially the same as that described in Fig. 1. A car entering the section at the right closes a circuit from trolley-wire 1 through contact 2, resistance 5 and answer-back lamp 6 in parallel, through the coils of the polarized counting-in magnet 14, line-wire 11, coils of the polarized counting-in magnet 14', resistance 12' to ground. Resistance 12 forms a branch circuit to ground, as in Fig. 1. The polarizing coils of counting-in magnets 14 and 14', instead of being connected permanently to the trolley-wire, may be connected as shown, since it is not necessary that they should be energized, except when the main coils of the counting-in magnets are energized. Since the magnets 14 and 14' are polarized, magnet 14' alone is actuated, ratchet 13' is shifted one step, bringing contact arm 17' into engagement with its back contacts and dropping banner 19' to danger position. The circuit of the red or danger lamp 20' is slightly different from 120

that shown in Fig. 1. This circuit extends from trolley-wire 1 through resistance 24' and 21' and lamp 20' to the middle back contact of arm 17', and thence to ground. 5 This lamp is thus lighted when the banner 19' is thrown to danger position. The circuit of the lamp 23, which acts as a caution signal, extends from trolley-wire 1 through resistance 24, lamp 23, front contacts of arm 17, line-wire 22, lower back contacts of arm 17', and counting-out magnet 15' to ground. The upper back contacts on arm 17' serve to connect contact 2 to the connection between relay 14' and line-wire 15, to take care of a car over-running the danger signal in the same way as this event is provided for in the arrangement of Fig. 1. Additional contacts 25 and 25' are placed on the armatures on counting-out magnets 20 15 and 15'. The purpose of these contacts is to maintain closed the circuit of the counting-out magnets during the movement of the ratchet-wheel over its last step when being returned by the counting-out magnet 25 to its normal position. This movement of the ratchet through its last step, by shifting the contact arm from its back contacts, would otherwise open the circuit of the counting-out magnet by disconnecting it 30 from line-wire 22. By providing the contacts on the armature of the counting-out magnet, a shunt circuit from line-wire 22 to the counting-out magnet is closed before or just as the pawl carried by the armature 35 engages and shifts the ratchet-wheel. It will be understood that these contacts should be so arranged as to permit a further movement of the armature of the counting-out magnet after the contacts have been closed. 40 I have shown in Fig. 2, in connection with the lamps 20 and 20', an additional feature, which may be applied to the other lamps in the system, as well as to the lamps in the arrangement of Fig. 1. Its purpose is to guard 45 against the burning out of a signal lamp, which is especially likely to occur in an electric railway signal system, since the lamps must be supplied from the power-circuit, the voltage of which, in most railways, fluctuates greatly. I have shown in Fig. 2, lamp 50 20 shunted by the lamp 26 and a resistance 27 in series. If lamps 20 and 26 are designed for the same voltage, and if resistances 24 and 21 are proportioned to give the 55 normal lamp voltage at the terminals of lamp 20, the voltage at the terminals of lamp 26 will be below normal, while lamp 20 is burning; but if lamp 20 is burned out, the voltage-drop across resistances 24 and 21 60 decreases, because of the decrease in current flow, so that the voltage across the terminals of lamp 26 increases, and if resistance 27 is properly proportioned, the voltage at the 65 terminals of lamp 26 will then be the normal voltage of the lamp. If the voltage of

the power-circuit is approximately 550, as it is in most direct-current roads, and if standard 110-volt lamps are used, the voltage-drop across resistances 24 and 21, when both lamps are burning, should be approximately 70 440 volts,—that is, the amount of these resistances should be approximately four times the resistance of the parallel circuit formed by lamp 20, and lamp 26 and resistance 27. Now, if resistance 27 is made approximately equal to that of a standard 110-volt lamp, then, if lamp 20 burns out, the voltage across the terminals of lamps 26 will be approximately 110 volts. It follows 75 from this that if standard 110-volt lamps are employed, one of these lamps may form the resistance 27. I have consequently shown two lamps 26' in series, shunting the lamp 20'. If all three lamps are 110-volt lamps, this combination gives the voltage 80 85 relations desired.

It will be understood that I have illustrated my invention diagrammatically, but any suitable construction may be employed for the several parts of the apparatus.

I do not desire to limit myself to the particular construction and arrangement of parts here shown, but aim in the appended claims to cover all modifications which are 90 within the scope of my invention.

What I claim as new and desire to secure by Letters Patent of the United States, is

1. In a signal system for electric railways, a line-wire extending through a single-track section, a polarized magnet connected to each end of said line-wire, a resistance connected between each magnet and ground, a contact at each end of the section connected to the connection between the magnet and resistance at that end of the section and arranged to be connected to the source of power current when a car enters the section at that end, and signal mechanisms controlled by said magnets.

2. In a signal system for electric railways, a line-wire extending through a single-track section, a polarized magnet connected to each end of said line-wire, a resistance connected between each magnet and ground, a contact at each end of the section connected to the connection between the magnet and resistance at that end of the section and arranged to be connected to the source of power-current when a car enters the section at that end, a step-by-step device controlled 110 by each magnet, and a signal controlled by 115 each device.

3. In a signal system for electric railways, a line-wire extending through a single-track section, a polarized magnet connected to 125 each end of said line-wire, a resistance connected between each magnet and ground, a contact at each end of the section connected to the connection between the magnet and resistance at that end and arranged to be 130

- connected to the source of power-current when a car enters the section at that end, signal mechanisms controlled by said magnets, and means controlled by each signal mechanism for establishing a connection from the contact at that end of the section to the line-wire at a point between said magnets. 5
4. In a signal system for electric railways, a line-wire extending through a single-track section, a polarized magnet connected to each end of said line-wire, a resistance connected between each magnet and ground, signal mechanisms controlled by said magnets, and means for supplying current to the connection between the magnet and the resistance at either end of the section when a car enters the section at that end. 10
5. In a signal system for electric railways, a line-wire extending through a single-track section, a polarized magnet connected to each end of said conductor, a resistance connected between each magnet and ground, signal mechanisms controlled by said magnets, means for supplying current to the connection between the magnet and the resistance at either end of the section when a car enters the section at that end, and means controlled by the signal mechanisms for supplying current directly to the line-wire when a signal at one end of the section is at danger and a car enters the section at that end. 15
6. In a signal system for electric railways, a line-wire extending through a single-track section, a signal-controlling magnet and an indicating device connected to each end of said line-wire, means for supplying current to said line-wire through the magnet and device at one end when a car enters the section at that end, said device being non-responsive to a current sufficient to operate said magnets, and means controlled by the operation of the magnet at the other end of the section for increasing the current in the line-wire to cause the device at the end of section entered by the car to give its indication. 20
7. In a signal system for electric railways, a line-wire extending through a single-track section, a signal-controlling magnet and a return-indication device connected to each end of said line-wire, means for supplying current to said line-wire when a car enters the section at one end to actuate the magnet at the other end, and means controlled by said magnet for controlling the indication of the device at the end entered by the car. 25
8. In a signal system for electric railways, a line-wire extending through a single-track section, a polarized signal-controlling magnet and a return-indication device connected to each end of said line-wire, a resistance connected between each magnet and ground, means for supplying current to the connection between the magnet and the resistance at either end of the section when a car enters 30
- the section at that end, and means controlled by each magnet for short-circuiting a portion of the resistance connected between it and ground. 35
9. In a signal system for electric railways, a line-wire extending through a single-track section, a polarized signal-controlling magnet connected to each end of said line-wire, a resistance connected between each magnet and ground, a contact at each end of the section connected to the connection between the magnet and resistance at that end of the section and arranged to be connected to the source of power-current when a car enters the section at that end, a return-indication device in series with the contact connection, and means controlled by each magnet for short-circuiting a portion of the resistance connected between it and ground. 40
10. In a signal system for electric railways, a line-wire extending through a single-track section, a signal controlling magnet and a return-indication device connected to each end of said line-wire, means for supplying current to said line-wire at either end when a car enters the track section at that end, the magnet at the other end of said line-wire alone being connected and arranged to respond to said current, and means controlled by said magnet at the other end of said line-wire for modifying the current in said wire to cause the return-indication device at the end entered by the car to give its indication. 45
11. In a signal system for single-track sections of electric railways, a danger and a caution signal at each end of the section, means actuated by a car entering one end of the section for setting the danger signal at the other end, a line-wire extending through the section to which wire both caution signals are normally connected, and means controlled by each danger signal for disconnecting the caution signal at that end of the section from the line-wire, and establishing a connection to said line-wire for energizing the caution signal at the other end. 50
12. In a signal system for single-track sections of electric railways, a danger signal, a caution signal, and a controlling magnet at each end of the section, a line-wire extending through the section, and means controlled by the danger signal for connecting said caution signal and said controlling magnet alternately to said line-wire. 55
13. In a signal system for single-track sections of electric railways, a step-by-step device at each end of the section, a "counting-in" magnet and a "counting-out" magnet for each device, connections whereby the "counting-in" magnet at either end of the section is energized momentarily upon the entrance of every car at the other end of the section, a danger signal at each end actuated by the first movement of the step-by-step 60

device, a caution signal at each end, a line-wire extending through the section to which wire both caution signals are normally connected, and means controlled by the danger signal for disconnecting the caution signal from that end of the line-wire and connecting the "counting-out" magnet to said line-wire.

14. In a signal system for single-track sections of electric railways, a step-by-step device at each end of the section, a "counting-in" magnet and a "counting-out" magnet for each device, connections whereby the "counting-in" magnet at either end of the section is energized momentarily upon the entrance of every car at the other end of the section, a danger signal at each end actuated by the first movement of the step-by-step device at that end, a line-wire extending through the section to which wire both caution signals are normally connected, means controlled by the danger signal for disconnecting the caution signal from that end of the line-wire and establishing a connection 25 to said line-wire through the "counting-out" magnet at that end for energizing the caution signal at the other end, said magnet being non-responsive to the current energizing said caution signal, and means connected to said line-wire for increasing the current-flow through said magnet when a car leaves the section at either end.

15. In a signal system for single-track sections of electric railways, a step-by-step device at each end of the section, a "counting-in" magnet and a "counting-out" magnet for each device, connections whereby the "counting-in" magnet at either end of the section is energized momentarily upon the entrance of every car at the other end of the section, a danger signal at each end actuated by the first movement of the step-by-step device, a line-wire extending through the section to which wire both caution signals are normally connected, both of said caution signals being also normally connected to the source of power-current, means controlled by the danger signal for disconnecting the caution signal from that end of the line-wire and establishing a connection from said wire through the "counting-out" magnet to ground, the caution signal being of too high a resistance to permit enough current to pass to operate said magnet, and 55 means for establishing a low-resistance circuit from the source of power-current to said line-wire when a car leaves the section at either end.

16. In a signal system for single-track sections of electric railways, a danger signal, a caution signal, and an answer-back signal at each end of the section, signal con-

trolling apparatus at each end of the section including means for setting the danger signal at one end and the caution signal at the other end when a car enters the section at said other end, and means controlled by the apparatus at the exit end of the occupied section each time it is operated by cars entering the section for momentarily energizing the answer-back signal at the entering end.

17. In a signal system for single-track sections of electric roads, a step-by-step device at each end of the section, means for moving the device at either end one step when a car enters the other end of the section, a danger signal at each end arranged to be set by the first movement of the step-by-step device at that end, a caution signal at each end controlled by the danger signal at the other end, and an answer-back signal at each end controlled by each forward movement of the step-by-step device at the other end.

18. In a signal system for single-track sections of electric roads; a step-by-step device at each end of the section, means for moving the device at either end one step when a car enters the other end of the section, a danger signal at each end arranged to be set by the first movement of the step-by-step device at that end, a caution signal at each end controlled by the danger signal at the other end, and an answer-back signal at each end controlled by each forward movement of the step-by-step device at the other end, two line-wires extending through the section, and connections whereby the necessary circuit for each of the above operations is formed by one or the other of said two wires and a ground-return.

19. In a signal system for single-track sections of electric roads, a signal mechanism at each end of the section comprising a step-by-step device, a "counting-in" magnet, a "counting-out" magnet, a danger signal, a caution signal, and an answer-back signal, two line-wires connecting said mechanisms, and connections whereby the caution signal and one of said magnets at each end are controlled from the other end of the section through one of said line-wires and the answer-back signal and the other magnet at each end are controlled from the other end of the section through the other wire.

In witness whereof, I have hereunto set my hand this 27th day of November, 1907.

LAURENCE A. HAWKINS.

Witnesses:

BENJAMIN B. HULL,
HELEN ORFORD.
